CHARCOAL FIRE STARTER

George W. Haynes, 101 Summit Blvd.,
Englewood, Colo. 80909

Filed Nov. 26, 1971, Ser. No. 202,724

Term of patent 14 years

Int. Cl. D7—02

U.S. Cl. D48—27 C

FIG. 1.

FIG. 2.

FIG. 3.

FIG. 4.

FIG. 1 is a side elevation of a charcoal fire starter showing my new design;

FIG. 2 is a diametrical section showing the interior thereof in elevation;

FIG. 3 is a top plan view; and,

FIG. 4 is a bottom plan view.

The undisclosed side is identical to the side shown.

I claim:

The ornamental design for a charcoal fire starter, as shown and described.
